CLAIM

The ornamental design of a ventilation deflector unit, substantially as shown and described.

DESCRIPTION

FIG. 1 is a perspective view of a ventilation deflector unit showing my new design.

FIG. 2 is a top plan view thereof.

FIG. 3 is a side elevational view thereof, the opposite side being a mirror image.

FIG. 4 is a bottom plan view thereof.

FIG. 5 is an end view of one end thereof.

FIG. 6 is a view taken from the end opposite that shown in FIG. 5.

FIG. 1

FIG. 2

FIG. 3

FIG. 4

FIG. 5

FIG. 6
